ELECTRON TUBE

Fritz Michelssen, Berlin, Germany, assignor to
 Telefunken Gesellschaft für Drahtlose Tele-
 graphie m. b. H., Berlin, Germany, a corpo-
 ration of Germany

Application August 8, 1932, Serial No. 627,928
 In Germany August 25, 1931

7 Claims. (Cl. 250—141)

The present invention relates to electron tubes and particularly to cathode ray tubes wherein an electron pencil is adapted to impinge upon a fluorescent screen to produce thereon luminous effects.

5 The arrangement and construction of a Braun tube, generally speaking, has always been so that the concentrated electron ray pencil is caused to impinge upon the center of the fluorescent screen 10 surface which it is to strike, as long as no deflective forces are brought to act upon the electron pencil.

An arrangement of this sort is well known in the prior art and usually consists of a tube 15 wherein the axis of the electrode system generating and deflecting the cathode-ray pencil coincides with the central axis of the vessel so that the projection of the system of deflector plates upon the fluorescent screen comes to lie 20 in the center thereof. For a great many purposes this arrangement is of advantage, for instance, where the recording of alternating current curves, recording of hysteretic loops or the like, is concerned.

25 According to the present invention, however, this type of revolution-symmetric construction usually employed in the prior art is abandoned. Such a scheme is of great advantage for a number of other practical applications of a Braun or 30 cathode ray tube. In instances, whenever the point is (as, e. g., in television work) to scan the screen, starting from the origin of a coordinate system, in two directions at right angles to each other by means of a cathode ray pencil or spot, 35 it is of greater advantage to remove the starting spot of the cathode ray pencil from the center of the screen towards the edge or margin or into a corner of the scanning surface. In the case of a structure, that is, the form of construction, 40 presenting rotational symmetry, scanning from a point as stated can be accomplished only by first bringing the pencil to a point close to the edge of the screen by the action of electric or magnetic deflection. If, in order to avoid the irreg- 45 ular or non-uniform luminous excitation of the screen caused by sinuous alternating current potentials recourse is had to what is known as "Kipp" oscillations whose potentials cause the spot to scan the surface in two directions, start- 50 ing from a coordinate origin, then special circuit means must be provided whereby the origin of the coordinate system, that is, the stationary spot of the pencil in the absence of deflecting "Kipp" oscillations, is shifted towards the edge 55 of the luminescent screen. The provision of such

means is obviated according to the present invention.

According to this invention the construction of the tube is made so that the electrode system, cross-sectionally speaking, does not appear to be projected upon the center of the screen, but at a point close to the border thereof. In other words, the trace or contour of the cathode ray pencil is not situated in the center of the screen surface but rather marginally on the part of 10 the impinging surface to be scanned thereby, in the absence of deflective fields. This is accomplishable by a suitable arrangement of the electrode system inside the tube or by choosing convenient forms for the tube or vessel. The most 15 preferable plan in this connection is to proceed in such a way that the axis of the electrode system falls outside the median axis of the vessel.

The basic idea of the invention is illustrated by way of example by the accompanying drawing, 20 wherein:

Fig. 1 represents a longitudinal section through the tube; Fig. 2 represents a cross-section of one end of the tube; and Fig. 3 represents a modified form of the tube shown by Fig. 1.

25 The glass support (not shown) carrying the tube cathode and anode electrodes 1 and 3 may be welded fast in the glass bulb 4 eccentrically rather than concentrically or symmetrically. The electric or magnetic deflector systems 5 and 30 7 disposed either inside or outside the vessel, according to the present disclosure, should then be so arranged that the electron pencil 9, in the directions at right angles to each other, is able to scan the same distance as far as the next 35 edge of the screen 11.

In such an eccentric form of tube there arises this drawback that when scanning the entire picture surface, the punctiform pencil 9 does not exhibit throughout the same sharpness owing to 40 the fact that the distances or the paths passed by the pencil are of dissimilar lengths. Furthermore, owing to the steadily changing angle of the pencil relative to the picture surface there might easily occur a distortion or an unequally 45 intense excitation of the picture where large areas are concerned.

This difficulty as outlined in Fig. 3 is obviated by arranging the eccentric construction of the electrode system relative to the picture surface 50 and also the impinging surface at such an angle of inclination relative to the nondeflected pencil that like length of rays is insured for all directions when the pencil is deflected.

Having now described my invention, what I 55

claim and desire to secure by Letters Patent is the following:

- 5 1. A cathode ray tube comprising an electrode system including an electron source and a co-operatively arranged anode through which the developed electrons are projected as an electron beam, screen structure positioned within the tube eccentrically with respect to the axis of the electrode system, said screen structure being adapt-
10 ed to become fluorescent under the influence of the electron beam, and deflecting means axially aligned with the beam developing electrode system and positioned eccentrically with respect to the screen to cause when electrical energy is
15 supplied thereto the generated electron beam to traverse the screen structure.
2. A cathode ray tube comprising an electrode system including an electron source and a co-operatively arranged anode through which the generated electrons are projected as an electron beam, an electron responsive screen structure located within the tube and positioned eccentrically and angularly tilted with respect to the electrode system, and deflecting means axially aligned with respect to the electrode system to cause when electrical energy is applied thereto the generated electron beam to traverse the screen structure.
3. A cathode ray device comprising an envelope including an electrode system comprising a cathode and an anode for generating an electron beam adapted to be projected axially therethrough, screen structure provided at the opposite end of the envelope opposite the source of the electron beam and positioned eccentrically with respect to the axis along which the generated electron beam is projected so that the electron beam in its normal uncontrolled path impinges only upon an edge portion of the screen, and deflecting means axially aligned with respect to the electrode system for causing the electron beam generated to traverse the screen under the application of suitable deflecting voltages upon the deflecting means.
4. An electron tube comprising a fluorescent screen positioned at one end of the tube substantially normal to the longitudinal axis of the tube, gun structure for developing a beam of electrons mounted at the opposite end of the tube in an angular position relative to the longitudinal tube axis for directing the normal, undeflected beam upon the edge portion of the screen, only, and an electron beam deflecting system supported in axial alignment with the gun structure and also positioned at an angle with respect to the longitudinal tube axis.
- 5 5. In an electron tube, a fluorescent screen positioned at one end of the tube in a position substantially normal to the longitudinal axis of the tube, an electron gun structure positioned at the opposite end of the tube and arranged in an angular position relative to the tube axis so that the electron beam passing beyond the gun structure in the direction of the screen is normally incident upon the edge portion of the screen and an electron beam deflecting system supported in axial alignment with the gun structure and also positioned at an angle with respect to the tube axis.
- 10 6. In an electron tube, screen structure adapted to emit light upon the subjection thereof to an electron beam, an electron source, an anode arranged in co-operative relationship with said electron source so as to project a beam of electrons along a predetermined path corresponding substantially to the line drawn through the center of the source and the anode, said path being angularly displaced with respect to the longitudinal axis of the tube, and an electron beam deflecting system supported within the tube in equalized relationship with respect to the electron beam path so that the electron beam normally impinges upon the edge portion of the screen structure.
- 15 7. In electron tubes, a viewing screen, means for producing an electron beam and directing the developed electron beam toward the tube viewing screen along a path angularly disposed relative to the longitudinal axis of the tube so that the beam in normal position impinges upon one edge portion only of the screen, and a beam deflecting system in alignment with the normal path of the projected electron beam for causing the developed beam upon the application of suitable electrical energy to the deflecting system to sweep the entire screen structure.

FRITZ MICHELSSEN.
